UNITED STATES PATENT OFFICE.

DELLA M. GALOR, OF MAPLEVILLE, MARYLAND.

DESIGN FOR A TOY BANK.

SPECIFICATION forming part of Design No. 32,048, dated December 26, 1899.

Application filed November 13, 1899. Serial No. 736,887. Term of patent 3½ years.

To all whom it may concern:

Be it known that I, DELLA M. GALOR, a citizen of the United States, residing at Mapleville, in the county of Washington and State of Maryland, have invented a certain new Design for a Toy Bank; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to a design for a toy bank or money-box circular in outline with an ornamental obverse face and a figured circumference, the general design of the face and circumference of the bank being clearly illustrated in the drawings, in which I have shown, in—

Figure 1, a view of the obverse face of the bank, and in Fig. 2 a view of the reverse face of the bank, while Fig. 3 is an edge view.

Reference now being had to the details of

the drawings by letter, A designates the obverse face of the bank, circular in outline, and on said face appear two American flags with their staffs crossed, and over the point of intersection of said staffs appears a portrait of William McKinley, President of the United States.

About the circumference of the bank appear at the left of the slot-aperture a field of stars, while at the right of the slot is a series of stripes.

The reverse face of the bank is circular in outline, the surface of said reverse face being plain.

Having thus described my design, what I claim is—

The design for a toy bank as herein shown and described.

In testimony whereof I affix my signature in presence of two witnesses.

DELLA M. GALOR.
